UNITED STATES PATENT OFFICE.

JAKOB L. BERGVALL, OF NEWPORT NEWS, VIRGINIA.

PORTABLE HOUSE.

No. 859,727.

Specification of Letters Patent.

Patented July 9, 1907.

Application filed October 26, 1905. Serial No. 284,336.

To all whom it may concern:

Be it known that I, JAKOB L. BERGVALL, a subject of the King of Sweden, residing at Newport News, in the county of Warwick and State of Virginia, have invented 5 certain new and useful Improvements in Portable Houses, of which the following is a specification.

My said invention relates to improvements in portable houses.

The objects of the invention are the provision of a 10 house of this character, made of sections by which the house itself may be extended, or decreased, quickly and with facility; to provide interchangeable sections that may be used in different portions of the house; to provide overlapping cross bars on the sections to 15 guide and hold the same to desired position when being assembled; and to provide means for securing the sections together.

The invention consists of a house made up of interchangeable sections, the novel features, and combinations 20 and arrangements of which are hereinafter described in the specification, disclosed in the drawings, and pointed out in the claims.

Referring to the drawings: Figure 1 is a vertical cross sectional view of a house embodying the features of my 25 invention. Fig. 2 is a view in elevation, partly broken away, showing the front outside, and the rear inside of the house illustrated in Fig. 1. Figs. 3, 4, 5, and 6 illustrate different shapes and sizes of houses which may be constructed by the sections embodied in the 30 invention, Fig. 6 illustrating a double house. Figs. 7 and 8 are diagrammatic representations of other forms which may be built according to this invention. Fig. 9 illustrates in horizontal section, the construction of one of the corners of the house. Fig. 10 is a section on line 10—10 Fig. 2. Fig. 11 is a horizontal section of the outer corner taken at the line X—Z Fig. 7, and Fig. 12 is a similar section of the inner corner in the same figure. Fig. 13 is an enlarged view of the upper left hand corner construction in Fig. 1. Fig. 14 is a vertical section at the apex A of the roof in the double house shown in Fig. 6. Fig. 15 is a view on the joint line 14—14 in Fig. 6. Fig. 16 is a vertical section illustrating the support for the double sloped roof of Fig. 6. Fig. 17 is a section of a roof joint, at B, in Fig. 2, and 45 Fig. 18 is a modified construction of roof joint wherein tar paper is used.

As illustrated in Figs. 3 to 8 inclusive, the house may be made up into a variety of different forms and sizes, but the sections are duplicated, and interchangeable. 50 The foundation or support for the house consists of sections of timber, as 1, 1, of suitable sizes, rabbeted at the end as illustrated, and preferably detachably connected by the hooks 2 and eyes 3. Upon the timber sections 1 the superstructure is erected, and there held 55 in position by stringers 4, secured on top of the foundation. Against these stringers the bottom or lower side

portions of the sections are located. One of the sections, as 5, at the front, is provided with a door 6, and a second front section 7 is shown as having a window 8 therein.

As illustrated, for example, in Fig. 5, when it is desired to extend the front of the house, a blank section 9 may be employed, either between a door section and a window section, or at the left of a door section (Fig. 5) or in general, on either side of any other section. The 65 side sections 10, are preferably formed to slope at the top with the gable roof portion 11, and in some instances it is desirable to have a section 10' provided with a window. At the rear side of the house the sections 12 are made of the same width as the corresponding front 70 sections 5 and are similarly constructed. All the sections are made up of tongue and groove boards, the joints being illustrated at 14, and each section is provided with two or more battens 15, 15, to which the boards are secured, as by nails or screws.

The floor portion 16 rests upon the stringers 4 and the various side, rear, and front sections, are detachably secured together by hooks 17 and eyes 18, as is also the roof portion secured to the sides.

As illustrated the battens are arranged on the sections so that their ends overlap each other, and by this means the sections are guided into and held in alignment and position, vertically as well as laterally.

The roof portion at front and rear is provided with stringers or beams 19, 20, which, form between them a 85 space for the reception of the front sections 5 and rear sections 12, respectively; the roof portion being slipped down over the top of the vertical sections and holding them in place. The two inside stringers are foreshortened at their ends to allow the roof to overlap the side 90 walls of the house.

In Fig. 9 a common corner of the building is illustrated, and in Fig. 10, the joint between two aligned sections is shown. In these joints, as in other joints to be described the feather 21 is inserted to make the 95 joint weather tight. The corner construction of Fig. 9 shows a front section 5 and a side section 10, the permanent joint at the corner being a rabbet joint.

Fig. 11 indicates a double feather joint construction at the outside corner of a house as illustrated in Fig. 100 7, and Fig. 12 shows a similar double feather-joint at the inner corner Z of Fig. 7. In Fig. 12 an upright post 22 is provided with two feathers 21, 21, and the adjoining sections are grooved to seat over these feathers.

At the corner joints I preferably secure the strengthening blocks 23, 24, to secure rigidity and stability, said blocks being securely fastened to the adjoining corner sections, and overlapping the adjoining wall section like the overlapping battens in other joints.

The double house illustrated in Fig. 6 requires but 110 slight modification in its corner roof construction from single construction shown in Fig. 13.

In Fig. 14, the two stringers 19' 19' abut each other, and together with the pair of stringers 20' 20' form mortises for the reception of the sections 5', and these sections 5' may serve as blank partitions to form two 5 separate houses, or be provided with door ways, to provide two compartments in the same house. Or these sections 5' may be omitted making the whole one room in which case the roof will be supported by the girder in Fig. 16.

- 10 I have described hooks and eyes as the means for detachably securing the sections together, but for large houses, and to secure rigidity in some places, I employ bolts instead of hooks and eyes. For example, in Fig. 15, in securing the front sections of a double house, 15 where an upright post 25 is interposed between the adjoining sections, I provide each section with an angle iron 26, which may be secured to a strip or batten 15, as illustrated, and these angle irons have holes in them through which the bolt 26' is passed and secured by a 20 nut as 27. As many of these bolts may be used as is desirable, and it will be obvious that a secure and tight joint may be formed by this construction. Preferably a strip 28 is secured to the post 25 to cover the joints between the post and the sections, and give a finish to 25 the front appearance of the house. If desired, a girder or beam 29, having connected thereto short connecting pieces 30, and roof strips or girders 31, forming a framework for the support of the roof, may be used, and the pieces connected by plates as 32.
- 30 To insure a water tight joint and protection from the weather, a tin covering may be provided for the house as shown at 33, in Fig. 17, or tar paper 34, may be used as illustrated in Fig. 18.

From the above description taken in connection with the drawings, it is evident that I have provided a house which fulfills all the purposes and objects set forth heretofore. The house or sections are so constructed that by adding one or more sections, or by omitting one or more sections, various sizes and shapes may be produced. The sections are interchangeable, and the detachable connections insure a rapid erection and dismemberment of the house.

Having thus fully described my invention, what I claim as new and desire to secure by Letters Patent is:

1. A sectional house having feather joints between the sections, hooks and eyes on the sections for detachable connection therebetween, battens secured to each section adapted to overlap the adjoining sections, triangular corner blocks a floor, a detachable roof, and hooks and eyes for securing the roof to the house sections. 45

2. The combination in a sectional house of rabbeted stringers forming the foundation, a floor, sections provided with doors and windows, hooks and eyes for securing the sections together, feather joints between the adjoining sections, and overlapping battens carried by 55 the sections for guiding the sections in position and holding the same.

3. The combination in a sectional house of rabbeted stringers forming the foundation, hooks and eyes for connecting said stringers, a floor, sections provided with 60 doors and windows, battens on the sections overlapping each other and forming guides, hooks and eyes for securing the sections together, a roof, and hooks and eyes for securing the roof to the sections.

In testimony whereof I affix my signature in presence 65 of two witnesses.

JAKOB L. BERGVALL.
